UNITED STATES PATENT OFFICE.

HERMAN E. WOLKEN, OF LEIGH, NEBRASKA.

BOWLING-BALL CLEANER.

1,191,260.

Specification of Letters Patent. Patented July 18, 1916.

Application filed April 1, 1915. Serial No. 18,581.

To all whom it may concern:

Be it known that I, HERMAN E. WOLKEN, a citizen of the United States, residing at Leigh, in the county of Colfax, State of Nebraska, have invented certain new and useful Improvements in Bowling-Ball Cleaners; and I do hereby declare the following to be a full, clear, and exact description of the invention, such as will enable others skilled in the art to which it appertains to make and use the same.

This invention relates to improvements in attachments for bowling alleys.

The principal object of the invention is to provide a device for attachment to the ball return track of a bowling alley for removing dust and dirt from the balls.

Another object is to provide a simple device for attachment to the return track of a bowling alley through which the balls roll so that the dust and dirt will be automatically removed from the balls.

Other objects and advantages will be apparent from the following description when taken in connection with the accompanying drawing, in which:

Figure 1 is a side elevation of a portion of the return track of a bowling alley behind the foul line showing my invention mounted thereon, Fig. 2 is an enlarged vertical longitudinal sectional view through the cleaning device and portion of the track, Fig. 3 is a vertical transverse section on the line 3—3 of Fig. 1, and Fig. 4 is an enlarged vertical sectional detail of one of the brush members of the cleaner.

Referring particularly to the accompanying drawing, 10 represents the main return track of a bowling alley on which both ten-pin and duck-pin balls are adapted to roll. Disposed above this track is a second track 11 connected by an inclined section 12 on which the ten-pin balls roll toward the buffer post 13 disposed at the ends of both tracks 10 and 11. The tracks each comprise a pair of parallel rails, and secured

to the inner vertical faces of the rails of the track 11 are the longitudinal parallel strips 14 to which are secured the ends of a plurality of open rings 15 standing vertically above the track and transversely thereof, and in parallel relation to each other. A similar strip 16 is secured to the upper closed parts of the rings to hold them in proper alignment and in proper spaced position. Secured to the inner curved faces of the rings are the brushes 17 formed preferably of long soft hair. Thus there is provided a ring of inwardly directed bristles through which the balls 18 roll, the device forming in effect a tunnel for the balls. The hair being long and soft, there will be no retarding of the rotation of the ball, whereby the hair or bristles of the brushes will effectively act upon practically the entire surface of every ball as it passes through.

From the foregoing it will readily be seen that I have provided a simple, novel, and efficient device for the return track of a bowling alley, whereby the balls will be effectively cleaned before they are again used.

The device is of such a nature that it can be readily applied to the ordinary track of a bowling alley.

What is claimed is:

In a device of the class described, a plurality of metallic open rings having their ends turned outwardly, a strip secured to the upper closed portion of each of said rings to hold the latter in spaced relation, a pair of spaced parallel strips connecting the outturned ends at each side of said rings, and bristles projecting inwardly from the interior surface of each of said rings, substantially as described.

In testimony whereof, I affix my signature, in the presence of two witnesses.

HERMAN E. WOLKEN.
